UNITED STATES PATENT OFFICE.

ETIENNE POULIN, JR., OF ST. GERMAIN DE GRANTHAM, CANADA.

RAILWAY-CROSSING FROG.

SPECIFICATION forming part of Letters Patent No. 681,077, dated August 20, 1901.

Application filed March 28, 1901. Serial No. 53,203. (No model.)

To all whom it may concern:

Be it known that I, ETIENNE POULIN, Jr., a subject of the King of Great Britain, residing at St. Germain de Grantham, county of 5 Drummond, Province of Quebec, Canada, have invented certain new and useful Improvements in Railway-Crossing Frogs; and I do hereby declare that the following is a full, clear, and exact description of the invention, such as will enable others skilled in the art to which it appertains to make and use the same.

My invention relates to improvements in railway-crossing frogs wherein two tracks of 15 a railway cross each other at a right angle, and the object that I have in view is to provide a continuous bearing for the wheel-tread while passing the division at the intersection of the rails.

20 A further object of the invention is the provision of means for automatically shifting the position of the tread-bearing member by the action of the wheels on an approaching train, whereby said member is adapted to occupy 25 an operative relation to either of the two sets or pairs of rails at the crossing and to afford the desired continuous tread-bearing for trains traveling in either direction across the crossing.

30 With these ends in view the invention consists in the novel construction and arrangement of parts, which will be hereinafter more fully described and claimed.

In the accompanying drawings, forming a 35 part of this specification, Figure 1 is a plan view of my improved railway-crossing frog. Fig. 2 is a side elevation thereof looking at the lower side of Fig. 1. Fig. 3 is a section on the line 3 3 of Fig. 1. Fig. 4 is another 40 section on the dotted line 4 4 of Fig. 1. Fig. 5 is a plan view of the bed. Fig. 6 is an end elevation thereof. Fig. 7 is a cross-section on the line 7 7 of Fig. 5. Figs. 8 and 9 are perspective views of portions of the frog.

45 Fig. 10 is a perspective view of one wheel-actuated bar and its arm.

The same characters of reference denote like and corresponding parts in each figure of the drawings.

50 I will first proceed to describe the bed, on which all of the operating parts of the frog are supported. This bed is provided with a

raised bearing-surface 6, having an extension 7. Another bearing-surface 8 is provided on the bed, and the extension 7 and the bearing-surface 8 have the fulcrum-posts 9.

10 11 designate the two arresting-posts, which are fast with the bed and disposed between the bearing-surfaces 6 8, and the post 10 has its active surface *a* disposed at a right angle to the corresponding surface *b* of the post 11.

12 designates the tread-bearing member, the same being arranged to rest upon the bearing-surface 6 and to be shiftable with respect to the active faces *a b* of the arresting-posts 10 11. (See Fig. 1.) This tread-bearing member is represented in the form of a triangular block, which is arranged for its apex to lie adjacent to the two posts 10 11, 70 and said shiftable member 12 has two active faces *c d*, the former of which is adapted to lie in the plane of the active face *a* of the post 10 when said member 12 occupies the position shown in Fig. 1, but when the tread member is reversed or shifted to its opposite position the active edge *d* of said member lies in the plane of the active edge *b* of the other post, 11, as will be clearly understood by reference to Fig. 1.

80 The broad essential feature of this invention lies in the shiftable tread-bearing member adapted to have either of its edges *c d* disposed in operative relation to two sets of rails which cross each other at an angle, preferably at a right angle, and any suitable means may be adopted for automatically shifting the position of this tread-bearing member by an approaching train, whereby the member 12 is adapted to afford a support 90 for the wheel-treads and the edge *c* or *d* is so disposed with relation to the rails that the wheel-flanges will not strike the member 12 upon which the treads of the wheels are adapted to ride when the train passes over 95 the crossing.

As one means for actuating the tread member 12 I have shown a series of wheel-actuated bars 13 13^a and 14 14^a. The bars 13 13^a are in line with each other and with one rail of a track. The other pair of bars 14 14^a are also in line with each other and with one rail of a crossing track. The pairs of wheel-actuated bars are disposed so that one edge of the bars

of each pair will occupy an operative relation to the active edge of one post. In the example shown the bars 13 13^a are mounted on the bed so as to bring one edge thereof in the 5 plane of the active face *b* of the post 11, and in like manner the other pair of bars 14 14^a are mounted so as to bring one edge thereof in the plane of the active face *a* of the other post 10. Each wheel-actuated bar is hung at 10 a point intermediate of its length on a fulcrum-post 15 by means of the pivot-pin 15^a, and said bars are provided with arms as follows: The bar 13 has an arm 16, which extends toward an arm 17 on the bar 14^a, and 15 these two arms 16 17 are hung at their inner adjacent ends on short posts 20 20^a by means of the pivots 21. The bar 14 is provided with an arm 18, which extends inwardly toward a similar arm 19 on a bar 13^a, and these two 20 arms are fulcrumed at their inner adjacent ends on the short posts 22 by means of the pivots 22^a.

23 24 designate the evener-levers, each of which is fulcrumed at its middle, as at 25, on 25 the short post 26. The evener-lever 23 has its end portions pivoted, as at 27, to the pair of arms 16 17 of the bars 13 14^a, but the other evener-lever 24 has its end portions pivoted, as at 28, to the arms 18 19 of the bars 13^a 30 14. It will be observed that each evener-lever has each end portion pivoted to a wheel-bar arm at a point intermediate the length of the latter.

29 30 designate the actuators for the shift-35 able tread-bearing member, the actuator 29 being pivoted, as at 9, on the post of the bearing-surface 8, while the other actuator 30 is pivoted, as at 9, on the extension 7 of the bearing-surface 6. The actuator 29 is op-40 eratively connected with the arms 16 17 of the bars 13 14^a by means of the links 31 32, the same being pivoted at their outer ends at 33 33^a to said arms 16 17, while the inner ends of the links are pivoted at 34 to the actuator 45 29. The other actuator 30 is operatively connected to the arms 18 19 of the bars 13^a 14 by means of the links 35 36, the latter having pivotal connection at their inner ends, as at 37, to said actuator 30, while the other outer 50 ends of the links are pivoted at 38 38^a to the arms 18 19, respectively, of the bars 14 13^a. With the pivoted bars 14 14^a depressed to occupy substantially horizontal alinement with one rail of the track, the other pair of pivoted bars 13 13^a are raised to inclined positions, 55 and the several actuating devices are made to throw the tread-bearing member 12 into the position shown by Fig. 1, wherein the edge *c* of said member lies flush with the active edge *a* of the post 12 and with the edges of the depressed bars 14 14^a, whereby a train on the track-rail with which the bars 14 14^a are in alinement is adapted to have its wheel-treads ride upon the bars 14 14^a, the post 10 60 10 and the member 12, while the flanges of the wheel are free to pass through the space between said edge *c* of the member 12 and the

post 11. Trains on the same track are free to pass in either direction over and through the frog without disturbing the relation of 70 the parts; but when a train passes on the other track it crosses the first track at an angle through the frog, and the parts are automatically shifted in the following manner: As the wheel of the approaching train strikes 75 one of the bars 13 or 13^a both of said bars 13 13^a are simultaneously depressed through the action of the connecting mechanism, while the bars 14 14^a are elevated from a horizontal to inclined positions, thus reversing 80 the positions of the pairs of bars. This depression of the bars 13 13^a sets in motion the intermediate connecting mechanism by which the position of the tread-bearing member 12 is reversed, whereby said member is shifted 85 so as to bring its active edge *c* into alined relation with the corresponding edge *b* of the post 11 and with one edge of the bars 13 13^a. The gap or space between the member 12 and the post 11 is closed by the shifting of 90 the member, and at the same time a space is opened between the edge *d* and the post 10, so as to permit of the passage of the wheel-flanges between the member and said post 10, while the edge *d* of said member affords the 95 desired continuous tread-bearing through the frog.

Changes within the scope of the appended claims may be made in the form and proportion of some of the parts, while their essential features are retained and the spirit of the invention is embodied. Hence I do not desire to be limited to the precise form of all the parts as shown, reserving the right to vary therefrom.

I claim—

1. In a railway-crossing frog, the combination of wheel-actuated bars hung to vibrate on horizontal axes and arranged in pairs and with the bars of one pair disposed in the same 100 vertical plane, limiting-posts in the planes of the respective pairs of bars, a shiftable tread-bearing element in active relation to one pair of bars and one limiting-post, actuators disposed on opposite sides of the tread-bearing 105 element, and connections between the actuators and the bars of opposite pairs, substantially as described.

2. In a railway-crossing frog, the combination of limiting-posts having their active faces 110 disposed in planes intersecting at an angle corresponding to the position of crossing track-rails, a shiftable element having its active edges disposed correspondingly to the edges of the posts and arranged to be shifted 115 with respect to said posts for the formation of a gap or space between one edge and one post, wheel-actuated bars arranged in pairs in alinement with said posts, and means operatively connecting said bars with the shiftable element, substantially as and for the 120 purposes described.

3. In a railway-crossing frog, the combination of two pairs of wheel-actuated pivoted

bars disposed at an angle one to the other, a shiftable tread-bearing element arranged in operative relation to the bars of one pair, inwardly-extending arms on the bars of the opposite pairs, evener-levers each hung between the bars of opposite pairs and having operative connection with the arms of said bars, and the actuators independently pivoted to the shiftable tread-bearing element and each

linked to the arms of opposite pairs of wheel-actuated bars, substantially as and for the purposes described.

In witness whereof I have hereunto set my hand in the presence of two witnesses.
